UNITED STATES PATENT OFFICE.

WILLIAM H. HOLMES, OF WALKERVILLE, ONTARIO, CANADA.

HYDROCARBON MOTOR.

Application filed April 29, 1920. Serial No. 377,601.

This invention relates to hydrocarbon motors, and more particularly to methods of, and means for muffling the exhaust gases of such motors.

As is well known, the exhaust gas issuing from the exhaust manifold of a hydrocarbon motor and coming into contact with the atmosphere, causes a series of reports or explosions. The exhaust gas issues in an intermittent stream of puffs or gas masses and each of the spaces between the puffs contains gas of less density than the gas puffs and the explosions or reports are caused by the contact of the intermittent stream of gas with the air.

Since the reports referred to are thus due to the contact of the intermittent stream of gas with the air, it will be evident that if the gases from the exhaust manifold could be made to issue in a continuous stream instead of in an intermittent stream, the source of the reports would be eliminated.

This invention has for its object, therefore, to eliminate the noise or the report of the exhaust gases of a hydrocarbon motor.

Another object of the invention is to separate and reunite the masses of gas in the intermittent stream of exhaust gases in such a manner that the gas will issue in a continuous stream.

Another object of the invention is to provide a muffler which may be manufactured cheaply and that will effectively eliminate the noise from the exhaust of a hydrocarbon motor.

Another object of the invention is to provide a novel method of muffling the exhaust gases of a hydrocarbon motor.

Further objects will appear from the following description taken in connection with the drawings in which:

Fig. 1 is a view in side elevation of one form of muffler embodying my invention, a portion of this figure being broken away and shown in section;

Fig. 2 is a longitudinal, sectional view of the construction shown in Fig. 1 and illustrating the theory of operation of the muffler;

Fig. 3 is a view illustrating in side elevation, another form of the invention; and

Fig. 4 is an elevational view similar to Fig. 1 but illustrating another form of the muffler, this form being particularly adapted for experimental work.

The method of muffling the exhaust gases

in the embodiment of the invention to be described consists briefly of separating and reuniting the masses or puffs of gas in the intermittent stream of exhaust gases in such a manner that the stream will be changed from an intermittent stream into a constant stream, or, stated in other words, the method consists of filling in the spaces between the consecutive puffs or masses of gas in such a manner that a continuous stream of gas is formed.

The structure, by means of which the method is carried out, comprises a plurality of conduits, preferably two, of different lengths, each conduit receiving a portion of the intermittent stream of gas from the exhaust manifold, the lengths of the conduits being so proportioned that the spaces between consecutive puffs of gas in one conduit will be filled in by puffs of gas from the other conduit or conduits, thereby changing the stream from an intermittent into a continuous stream of uniform density.

Referring to the drawings, I have shown in Fig. 1, a muffler comprising a conduit 10, which may be attached in any suitable manner to the exhaust manifold of a hydrocarbon motor, this conduit being divided into a conduit 11, which may be termed, for convenience, the main conduit, and a conduit 12, which may be termed a branch conduit. It will be seen that the branch conduit 12 is longer than the main conduit and in this instance the two conduits 11 and 12 are substantially equal in cross-section, and this being true, it will be at once evident that the masses or puffs of gas passing through the branch conduit 12 will travel through a greater distance than those passing in a straight line through the conduit 11, before the streams are reunited in the common exit conduit 13. The lengths of the main and branch conduits are so proportioned that the spaces between consecutive masses or puffs of gas passing through conduit 11, will, at the junction of the two conduits adjacent the common exit of the gases, be positioned opposite the puffs or masses of gas passing through the branch conduit 12 and in this manner, the spaces, each of which, as above stated, contains gas of less density, are eliminated by filling in these spaces with gas from the branch conduit. It will be noted that the conduit 13 is disposed at an angle to conduits 11 and 12, the longitudinal axis of the delivery conduit 13 being disposed in

100 105 110

a line substantially bisecting the angle between the axis of conduits 11 and 12. This arrangement tends to reduce to a minimum the friction of the gas on the walls of the delivery conduit.

In order to correctly apportion the gas between the main and branch conduits, a hinged gate 14 is mounted at the inlet junction of the conduits 11 and 12 and is adapted 10 to be adjusted by means of a handle 15, secured to the pivot pin 15' of the gate. It should be understood that the device will operate successfully without the gate, but that the gate is added as a refinement and 15 in order to give a more accurate adjustment for the apportionment of the gases. The gate 14 has also the added function of a cut-out since when positioned to cut off the gas from branch conduit 12, all of the gas will 20 be directed through the main conduit 11.

In Fig. 4 I have illustrated a form of the muffler particularly adapted for experimental work in determining the relative lengths of the main and branch conduits, and in this 25 form the conduit 10 is provided with an upwardly inclined open ended branch conduit section 16 at the inlet end of the muffler. A main conduit 11 is provided as before, and at the exit end of the conduit 11 there is integrally formed therewith, an oppositely extending inclined open ended branch conduit 17. The conduit 11, in this instance, is made 30 in sections, the two sections 18 and 19, having formed thereon, screw threaded portions 35 20 and 21, these portions being provided respectively with right and left hand screw threads. A sleeve 22 joins the two sections 18 and 19, this sleeve also having at its opposite ends right and left hand threads. 40 The two branch conduit sections 16 and 17 are connected by means of a flexible branch conduit 23 which may be formed of any suitable flexible material. The relative lengths 45 of the main and branch conduits of this muffler are changed by means of the threaded sleeve 22, since the rotation of this sleeve lengthens or shortens the main conduit 11. By means of this adjustment, therefore, the 50 lengths of the conduits may be so proportioned as to deliver the puffs of gas from the branch conduit in a position to completely fill in the spaces formed between consecutive puffs of gas in the main conduit. After 55 these lengths have been so determined for any particular motor, the muffler may be made up as shown in Fig. 1, with the main conduit and branch conduit having a fixed relation to each other as regards their 60 lengths. It will be understood that a slight overlapping of the puffs, after the streams of gas are reunited, and due to change of speed of the motor or other causes, will not detract from or be detrimental to the muffling action of the device.

65 In Fig. 3 I have illustrated another form

of muffler, this form being adapted for use in connection with motors in which the single branch conduit may not properly position the puffs or masses of gas to fill in the spaces between the consecutive puffs of 70 gas passing through the main conduit and this condition may arise with a multicylinder motor or under certain conditions of speed or motor performance. This form of the invention comprises a conduit 24 which 75 is adapted to be secured to the exhaust manifold of the motor, this conduit being subdivided into a main conduit 25 and a plurality of branch conduits 26 and 27. These branch conduits are made of such lengths 80 with respect to the length of the main conduit that the conduit 26 will deliver a puff of gas in position to partially fill the space between consecutive puffs in the main conduit 25, and the conduit 27 will deliver a 85 puff of gas so positioned as to fill the remaining space between the consecutive puffs in the main conduit. It will be obvious that more branch conduits may be added, if desired, and also that the sizes and lengths of 90 these conduits may, by experiment, be so determined as to entirely fill in the spaces between the consecutive puffs of gas passing through the main conduit.

Inasmuch as the theory of the operation 95 of the muffler has been outlined in the preceding description, a further detailed description of the operation is not deemed necessary.

From the above specification it will be 100 seen that I have provided a simple and effective method of muffling the exhaust gases of a hydrocarbon motor by changing the intermittent stream of gas into a continuous stream, thereby eliminating the 105 noise of the exhaust. It will also be clear that the construction by means of which this method is carried out, is simple and that this construction will be effective in operation and moreover may be cheaply manufactured.

While I have in the above specification described certain specific embodiments of the invention, it will be evident to those skilled in the art, that further modifications 115 and changes may be made in the method and in the construction and arrangement of the various parts without departing from the spirit or scope of the invention as expressed 120 in the following claims.

Having thus described my invention, what I claim and desire to secure by Letters Patent is:—

1. A muffler for hydrocarbon motors comprising a plurality of conduits, one of said 125 conduits having means for adjusting its length and another of said conduits being flexible.

2. A muffler for hydrocarbon motors comprising a plurality of conduits, one of said 130

conduits being sectional and having adjustable coupling means for said sections and another of said conduits being formed of flexible material.

3. A muffler for hydrocarbon motors comprising a pair of conduits of different lengths, said conduits opening into each other at their ends, one of said conduits be-

ing sectional and having adjustable coupling means for said sections, and the other 10 of said conduits being flexible.

4. A muffler comprising a plurality of conduits, one of said conduits being rigid and another of said conduits being flexible.

In testimony whereof I affix my signature.
WILLIAM H. HOLMES.
